UNITED STATES PATENT OFFICE.

WALTER MINNICH, OF MONTREUX, SWITZERLAND, ASSIGNOR TO SOCIETY OF CHEMICAL INDUSTRY IN BASLE, OF BASEL, SWITZERLAND.

PREPARATION OF SOLUTIONS OF COMPOUNDS INSOLUBLE OR SPARINGLY SOLUBLE IN WATER.

No Drawing. Application filed November 10, 1924, Serial No. 749,046, and in Switzerland November 19, 1923.

The invention relates to the preparation of solutions of compounds insoluble or sparingly soluble in water by using phenylacetylene as a solvent.

5 I have found that phenylacetylene is capable in a high degree of dissolving certain therapeutic compounds, especially camphor or mixtures of camphor with lipoids, such as for instance cholesterol or esters 10 of saturated or unsaturated organic acids with cholesterol, and the like, and that the solutions thus obtained may be injected subcutaneously or intramuscularly without causing any irritation. The solutions may 15 also be employed for percutaneous use according to the properties of the dissolved compounds.

The solutions obtained according to the present invention are thus useful for a large 20 variety of purposes, particularly in human or veterinary medicine.

Example 1.

50 parts of phenylacetylene are introduced 25 into 50 parts of camphor. The camphor readily dissolves completely. The mobile solution thus obtained is filtered, if necessary, and may be employed for injections without any further treatment.

Example 2.

30

Analogous solutions may be obtained with 50 parts of phenylacetylene, 50 parts of camphor and from 6-10 parts of the cholesterol ether of phenylpropionic acid or crotonic 35 acid, or other unsaturated organic acids. Of course, instead of a cholesterol ether in this example cholesterol itself or another lipid may be employed.

What I claim is:

1. As an article of manufacture, solutions of camphor in phenylacetylene.
2. As an article of manufacture solutions of camphor and lipoids in phenylacetylene.
3. As an article of manufacture, solutions 45 of camphor and cholesterol in phenylacetylene.
4. As an article of manufacture, solutions of camphor and esters of cholesterol in phenylacetylene.
5. As an article of manufacture, solutions 50 of camphor and unsaturated acid esters of cholesterol in phenylacetylene.

In witness whereof I have hereunto signed my name this 27 day of October, 1924.

WALTER MINNICH.
